UNITED STATES PATENT OFFICE.

WILLIAM BELL, OF BAY SIDE, NEW YORK.

SAFETY OIL-CAN.

SPECIFICATION forming part of Letters Patent No. 585,500, dated June 29, 1897.

Application filed February 8, 1897. Serial No. 622,521. (No model.)

To all whom it may concern:

Be it known that I, WILLIAM BELL, of Bay Side, in the county of Queens and State of New York, have invented a new and Improved 5 Safety Oil-Can, of which the following is a full, clear, and exact description.

The object of the invention is to provide a new and improved safety oil-can, more especially designed for filling oil-lamps, and arranged to prevent overflow by closing the air-inlet to the oil-lamp and giving a signal to the operator that the lamp is filled to the proper level, the device also indicating when the can is empty and the lamp is not filled to 15 the proper height.

The invention consists principally of an air-inlet pipe for the oil-can and extending from the nozzle thereof into the upper end of the can, and a vessel adapted to contain a 20 liquid and connected with the said air-inlet or vent pipe, the vessel being also provided with an air-inlet opening into the liquid below the level thereof.

The invention also consists of certain parts 25 and details and combinations of the same, as will be fully described hereinafter and then pointed out in the claims.

Reference is to be had to the accompanying drawings, forming a part of this specification, 30 in which similar characters of reference indicate corresponding parts in all the figures.

Figure 1 is a side elevation of the improvement. Fig. 2 is a sectional side elevation of the same on the line 2 2 of Fig. 3 and as applied for filling the lamp, and Fig. 3 is a plan view of the improvement.

The oil-can A is provided with the usual nozzle B, adapted to be passed with its outer end into the fount of the lamp to be filled, the 40 nozzle being provided with an adjustable stop C, adapted to limit the distance the free end of the nozzle is to pass into the fount of the oil-lamp by the said stop abutting against the filling-nozzle of the fount. From the free 45 end of the nozzle B extends an air-inlet or vent pipe D, opening into the upper end A' of the can A, so as to supply the latter with the necessary air to insure a free flow of the oil from the can A, through the nozzle B, into 50 the fount of the lamp.

The can A is provided at its upper end with the usual filling-spout normally closed by a

suitable cap E', so that air can only pass into the can A by way of the vent-pipe D. The latter is connected by a branch pipe F with 55 the upper end of a closed vessel G, preferably made of glass and set in a recess A², formed in the wall of the upper end A' of the can. A suitable band H extends across the vessel G, so as to hold the same permanently in position in its recess A². The vessel G is adapted to be filled with water or other liquid, and a pipe I extends into the vessel to within a short distance of the bottom thereof, the outer end of the pipe being provided with a nozzle I' 65 for supplying the vessel with the necessary liquid.

Now when the can is used for filling the lamp, as shown in Fig. 2, air passes into the can by way of the vent-pipe D, and when the 70 fount of the lamp is finally filled to the proper level the oil extends into the outer end of the vent-pipe D, so as to prevent air from passing through the vent-pipe into the can A to retard the flow of the liquid from the can 75 through the nozzle B. As the oil still flows from the can A a vacuum is formed, and consequently air is sucked through the pipe I into the vessel G, the air passing in bubbles through the liquid contained in the vessel to 80 finally pass by way of the branch pipe F and vent-pipe D into the can A. Now it is evident that the operator is at once notified of the filling of the lamp to the proper level as soon as the bubbles make their appearance 85 in the vessel G.

In case the can A runs empty while filling the fount and before the latter is filled to the proper level the operator soon discovers this fact, as the bubbles do not appear in the vessel G, thus indicating that the can A has run empty and the lamp-fount is not filled to the proper level. It will further be seen that the device is very simple and durable in construction and can be readily arranged on all kinds 90 of cans in use for the purpose described.

Having thus fully described my invention, I claim as new and desire to secure by Letters Patent—

1. A device of the class described, provided 100 with an air-vent pipe for the can, extending from the nozzle thereof into the upper end of the can, and a vessel adapted to contain a liquid and connected with the said vent-pipe,

the vessel being also provided with an air-inlet opening into the liquid below the level thereof, substantially as shown and described.

2. A device of the class described, comprising a vent-pipe for the can and extending from the nozzle thereof into the upper end of the can, a branch pipe leading from the said vent-pipe, a vessel carried by the can and adapted to contain a liquid, the upper end

of the vessel being connected with the said branch pipe, and an air-inlet pipe extending into the said vessel to within a short distance of the bottom thereof, substantially as shown and described.

WILLIAM BELL.
